UNITED STATES PATENT OFFICE.

LAUNCELOT GEORGE EGGLESTON AND EDWARD OLIVANT, OF LONDON, ONTARIO,
CANADA.

RAILROAD-CROSSING GATE.

1,171,110.

Specification of Letters Patent.

Patented Feb. 8, 1916.

Application filed January 21, 1914. Serial No. 813,448.

To all whom it may concern:

Be it known that we, LAUNCELOT GEORGE EGGLESTON and EDWARD OLIVANT, both of the city of London, in the county of Middlesex, in the Province of Ontario, Canada, have invented certain new and useful Improvements in Railroad-Crossing Gates, of which the following is the specification.

Our invention relates to improvements in railroad crossing gates and the object of the invention is to devise a simple, automatic mechanism whereby the gate is automatically raised and lowered by a train passing in either direction or in the case of 10 a double track to devise a mechanism by which the first train passing the crossing would lower the gate and the last train passing the crossing would raise the gate and it consists essentially of a lever swung 15 intermediately of its length and having a weight at one end, a rocking rod supporting the lever, a swingable gate arm, means for rocking the gate arm operated by the rocking rod, a rocking arm located at each 20 end of the crossing and at the side of each track and actuated by a passing train, a latch device located at the end of each crossing and at the side of each track and comprising a slidable notched bar and a latch 25 bar co-acting with the notch of the bar, a cable connection between the outer side of each rocking arm and the outer end of each notched bar, a cable connection between the 30 inner end of each notched bar at one end of the crossing, and the weighted end of the weighted lever, a cable connection between the inner end of the notched bars at the opposite end of the crossing and the free end of the weighted lever, and a cable 35 connection between the inner side of each rocking arm and one of the latched bars at the opposite end of the crossing as hereinafter more particularly explained by the 40 following specification.

Figure 1, is a general perspective view of a railroad crossing gate and operating mechanism. Fig. 2, is a detail of the operating lever. Fig. 3, is a detail of the locking latch.

In the drawings like letters of reference indicate corresponding parts in each figure. A and A' are a pair of tracks, the track A' comprising the rails A² and A³ and the track A comprising the rails A⁴ and A⁵. B and B' are swinging gate arms of the

crossing gate mounted on suitable standards B² and B³.

B⁴ is a pinion mounted on a stud B⁵ extending from each standard B² and B³.

C is a right angular arm connected to the pinion B⁴ so that the horizontal portion of the arm extends against the lower edge of the gate arm when in its raised position.

C' is a rocking rod journaled beneath the tracks A and A' and extending beneath the rails of the same.

C² is a quadrant gear arm mounted upon the rocking rod C' at each end thereof and meshing with each pinion B⁴.

E is a lever comprising arms E' and E² secured to the rocking rod C' and a weight E³ connecting the arms together at one end of the lever E.

F and F' and G and G' are train operating arms mounted on rocking rods F² extending beneath the rails A³ and A⁴ and journaled in suitable bearing brackets.

F⁴ is an arm secured to the opposite end of the rocking rod F² and provided with a roller F⁵ located slightly above the level of the crown of the rail A³.

F⁶ is a pin extending from each arm F and F'

F⁷ are slotted links mounted at their upper ends on the pin F⁶ and connected at their lower ends by the tension spring F⁸ to a suitable support.

2, 3, 4 and 5 are pulleys mounted on suitable brackets secured to the road bed.

6, 7, 8 and 9 are cables. The cables 6 and 9 extend from the left hand side of the levers F and G around the pulleys 2 and 4 and the cables 7 and 8 extend from the right hand side of the arms F' and G' around the pulleys 3 and 5.

H, H', H² and H³ are longitudinally movable locking bars, each provided with a notch H⁴ intermediately of their length. The locking bars H, H', H² and H³ are slidably held in suitable guiding brackets H⁶ and H⁷.

I are latch bars swung in suitable brackets I' and extending across each locking bar H, H', H² and H³ in proximity to one end thereof when the locking bar is in its normal position. The free ends of the cables 6, 7, 9 and 8 are connected to one end of each locking bar H, H', H² and H³.

9', 10 11 and 12 are cables extending from the opposite ends of the locking bars H, H', H² and H³ over suitable guiding pulleys to 110

the ends of the arms E' and E^2 of the lever E , the cables 9' and 11 being connected to one end of the arms and the cables 10 and 12 to the opposite end of the arms.

5 13, 14, 15 and 16 are tension springs interposed intermediately of the length of the cables 9', 11, 10 and 12.

17 and 18 are cables extending from the right hand side of the levers F and G over 10 suitable guiding pulleys through the slotted ends of the latch bar I . The free depending ends of each of these cables are provided with suitable weights 20.

18 J are inverted U-shaped guiding brackets extending over the latch bars I .

22 and 23 are cables extending from the left hand side of the arms F' and G' over suitable guiding pulleys and pass through the slotted ends of the latch bars I co-acting 20 with the slideable bars H and H^2 .

Having described the principal parts involved in our invention we shall briefly describe the operation of the same.

25 For the purpose of illustration we will say that the train is passing in the direction of arrow along the track A. The flange of the train contacts with the roller F^5 forcing the same and the arm G in the direction of arrow thereby pulling upon the cable 9 and 30 allowing the cable 18 to slacken, the weight 20 drawing it longitudinally. By this operation the locking bar H^2 is drawn longitudinally in the direction of arrow until the notch H^4 thereof passes beneath the latch bar I , such

35 bar dropping into the notch and locking the bar H^2 in a stationary position. The inward movement of the locking bar H^2 serves to place the spring 14 under tension. As soon as the tension of the spring 14 is suffi- 40 ciently strong the cable 11 draws upon the lever arm E^2 drawing it downwardly and raising the weight E^3 . This operation serves to rock the rocking rod C which throws the quadrant arm C^2 in the direction of arrow 45 revolving the pinion B^4 also in the direction of arrow and the arm C downwardly thereby freeing the gate arm B' which gradually falls gently and of its own weight toward its horizontal position.

50 In reference to the function of the springs 13, 14, 15 and 16, it may be stated, first, that by the springs stretching a little they relieve the tension and shock given to the cables 6, 9, 10 and 8 when the levers F or F' or G or G' 55 are moved by a train. The second purpose of each spring is to act as a means for moving the locking bar to which it is connected far enough to bring the groove from under the latch bar and thus prevent the latch bar

60 from falling back into the groove which it would do without the spring when two or more locked latch devices are unlocked at different times, the weight E^3 being prevented from doing its work until the last of the locking devices is unlocked by a train which

locked it. The springs are stretched when the latch bars fall into the grooves of the locking bar and remain stretched until the latch bars are pulled from the grooves, when by their contraction they instantly bring the grooves of the locking bars from under the latch bars.

65 After the train has passed the crossing the wheel flange engages the roller F^5 connected to the arm G' thereby throwing the arm G' in the direction of arrow. This operation

70 draws upon the cable 23 raising the weight 20 into engagement with the latch bar I thereby raising the free end of the latch bar

75 and carrying such bar out of the notch H^4 thereby freeing the bar H^2 which is carried back to its normal position by means of the tension spring 14 which has been placed in tension as previously described. If there is

80 a second train running in the same direction entering the crossing before the first train has left it will be readily understood that the train which first approaches the crossing will operate either the arm F or G drawing the locking bars H and H^2 longitudinally into the locking position thus both

85 bars will be locked and the gate arm held in its downward position until both trains have passed the crossing. The first train

90 passing the crossing will, of course, engage one of the arms F' and G' and free one of the locking bars H or H^2 but this operation,

95 of course, would not raise the gate as both locking bars must be free before the gate can be raised, each locking bar being connected to the lever E . If one locking bar is released the lever is held down by the other locking bar and until the second locking bar is released by the last train passing the crossing

100 no movement of the gate will take place.

105 As soon as the locking bars have been released as above described the weight E^3 serves to carry the lever back again to its normal position carrying the gear quadrant arm C^2 in the reverse direction to arrow

110 thereby raising the arm C upwardly carrying the gate arm to its normal position.

115 What we claim as our invention is:

1. In a railroad crossing gate, the combination with the swingable gate arms, of a rocking rod extending crosswise of the track and beneath the same, a counter balanced lever supported on the rod intermediately of its length, a counter weight carried on one end of the lever, means connected to the opposite end of the lever operated by an approaching train for raising and locking the arm in the raised position against the counter weight, and means for releasing the lever operated by the receding train, as and for the purpose specified.

120 2. In a railroad crossing gate for a double track, the combination with the swingable gate arms adapted to be placed on opposite sides of the track, of a rocking rod extend-

ing crosswise of the track and beneath the same, a turnable member supported in the gate arm support, a right angular bar carried thereby and designed to normally extend beneath the gate arm in its raised position, means operated by an approaching train for rocking the rod in one direction, connecting mechanism between the rocking rod and turnable member designed to rotate such turnable member and lower the right angular bar to free the gate arm, and means controlled by the receding train for rocking the rod in the opposite direction to raise the right angular bar and the gate arm supported thereby, as and for the purpose specified.

3. In a railroad crossing gate for a double track, the combination with the swingable gate arms adapted to be placed on opposite sides of the double track, a weight and mechanism operated by the weight for holding each gate arm in a raised position, of individual means actuated by each individual train approaching the crossing for raising the weight to allow the arms to swing downward, means located at each end of the crossing and at the side of each track for locking the weight in the raised position, means for individually actuating said locking means actuated by a train approaching the crossing, and means for individually releasing said locking means by means actuated by each train receding from the crossing whereby the weight is released by the locking means last released.

4. In a railroad crossing gate, the combination with the swingable gate arms, of a

rocking rod located beneath the tracks, a swingable arm located at each side of the crossing in proximity to the track rail, a counter-balanced lever mounted upon the rocking rod, a longitudinally movable notched locking bar, a suitably journaled pulley, a cable adapted to extend from one end of the notched locking bar around said pulley to the train operated lever at one side of the railroad crossing, a cable connecting the opposite end of the locking bar with the counter-balanced lever, a swingable slotted bar co-acting with the locking bar, and a cable connecting the slotted bar with the swingable lever located at the opposite side of the railroad crossing, as and for the purpose specified.

5. In a railroad crossing gate, the combination with the swingable gate arms, of a rocking rod extending crosswise of the track and beneath the same, a stud extending from the gate arm support, a pinion mounted on the stud, a right angular bar secured to the pinion and supporting the gate arm, a quadrant carried by the rocking rod and engaging the pinion, means operated by an approaching train for rocking the rod in one direction to release the gate arm and means controlled by the receding train to rock the rod in the opposite direction to raise the gate, as and for the purpose specified.
